NEWTON L. HALL, OF LA SALLE, ILLINOIS.

PERIMETRIC FEED FOR TUMBLING MILLS.

Application filed January 18, 1927. Serial No. 161,894.

This invention relates to means for feeding and circulating a load to and through a ball, tube, or other cylindrical grinding mill, the grinding medium being a tumbling load 5 of balls, pebbles, or rods and the invention particularly relates to means whereby the feed to the mill is caused to enter the mill at or near the axial line of the same and then is passed outward toward the perimeter of 10 the mill interior so that the feed can be delivered into the grinding chamber in the space above the load, thus eliminating the retardation of the feed by the obstruction due to load.

15 In present day practice in tumbling mills, the feed is delivered into the mill at or near its axial line and if the pulp or ball load within the mill has a depth which is above the center line or axis, it is required that the 20 feed of balls or pulp shall pass into the mill against its contained load. If this load is surcharged above this axis, it becomes difficult to cause the feed to enter the mill against this surcharged load. In order to lessen this 25 retardation, liquefying the pulp has been resorted to to make it flow readily but this detracts from the grinding efficiency of the load when this addition is made above a certain consistency of pulp. This consistency 30 is that attained when the particles of pulp will stick to and maintain an unwashed condition on the surface of the balls or rods. Good practice uses a ball load which is carried as high as operating conditions will permit and yet not detract from the largest 35 amount of feed which can enter the mill, this being, of course, coupled with other factors which give a maximum of grinding efficiency under operating conditions. A small 40 mill load will develop a mill product which is very different from that produced by a large load and for some products, particularly those which require uniformity in the graded sizes of the finer particles, the desired effects can only be secured by operating 45 with a surcharged load, that is, a load which fills the mill to above the axis thereof.

There is another and very important element which has to be considered in tumbling 50 mills. It is apparent that with a mill chamber entirely filled with a load, the center of gravity of the load will be identical with the axis of the mill and under these circumstances the power required for revolving the mill is only that necessary for overcoming 55 the friction of the bearings and the load inertia; the load being evenly balanced over the center line in all positions. As the load is diminished, with the mill under rotation, the center of gravity of the load will be at 60 a distance from the center of the mill and to the ascending side and this necessitates power being used to lift the load during rotation which is in addition to the power required for overcoming the mill and load inertia. 65 As the load is still further diminished, the center of gravity extends further from the mill center and the proportionate power requirement per unit of load is increased. It is obvious, therefore, that for an economical 70 power application per unit of load, it is necessary or desirable to have the center of gravity of the load as close to the mill center as possible. Speed conditions are variable under different conditions such as mill diameter, size and weight of load, etc., but in general there is an ideal peripheral speed for the mill load which is practically the same for mills of any diameter. The peripheral speed, however, is relatively slow in order 75 to secure the development of the proper cascade for the load.

Considering the cross section taken by a ball load during rotation of the mill, it will be observed that that part of the load which is on the ascending side is comparatively quiet. During rotation that part or sector of the load which is toward the exposed surface is falling as a cascade and upon reaching the bottom of its descent, the balls immediately enter the load in a comparatively fixed position but vary in position and pressure as they rise toward the zenith of their movement. This constant cascade and constant readjustment of the load parts develops 85 effects of both impact and attrition, the amount of these effects being governed by the speed of rotation, the weight and size of the load, and the impulse of migration developed in the load conditions. During 90 rotation the load parts are constantly undergoing a change of position in the load section and this is particularly the case when rods are used as a grinding medium as here a constant twisting of the rods is perceptible 95 even when they are in the ascending portion of the load. In a ball mill as well as a rod mill, all parts are constantly readjusting position and the heavier the load, the greater 100 will be the crushing and grinding effect on 105

particles of pulp between the grinding media. A small load has a comparatively small superimposed weight and accordingly a larger load will exert a correspondingly greater pressure on all of its parts and secure a better and finer grinding action.

The essential factors governing the efficiency of a ball mill are; its diameter and length; the speed of rotation; size of feed and discharge; volume of feed; amount of moisture in the pulp; load of balls; size and character of balls; hydraulic gradient of the pulp; character and position of discharge opening, and nature of material to be ground. Practically all mills use a hollow trunnion at the feed end of the mill through which the feed is delivered. Other types of mills have feed scoops placed around the shell of the mill midway of its ends, thus causing the pulp to migrate from the mid section towards either end trunnion. In none of them known to me is there a true perimetric feed or a feed which is discharged into the interior of the mill above the load line or the surface of the cascade and which, therefore, enters the mill unimpeded or unretarded by the load.

One of the specific objects of my invention is to provide a tumbling mill with a feed mechanism disposed entirely within the grinding chamber proper.

A further object is to provide for a perimetric feed into the grinding chamber and cause this feed to enter the grinding chamber at a point always above the cascade load.

Another object is to provide the mill with a perimetric feed including conduits, one delivering into the other, and the last named conduit into the grinding chamber, which delivers the feed to the grinding chamber either in a direction with or counter to the direction of rotation of the mill.

Still another object is to provide a perimetric feed of such character that two of the feeding elements may be disposed in balanced relation within the grinding chamber to thus overcome any tendency to unbalance the mill with its consequent requirement of increased power to run the mill.

Other objects will appear in the course of the following description.

My invention is illustrated in the accompanying drawings wherein:—

Figure 1 is a longitudinal sectional view of a tumbling mill having my invention applied thereto, the section being taken on the line 1—1 of Figure 2;

Fig. 2 is a section on the line 2—2 of Figure 1;

Fig. 3 is a fragmentary section on the line 3—3 of Figure 2;

Fig. 4 is a fragmentary section approximately on the line 4—4 of Figure 2;

Fig. 5 is a like section to Figure 2 but showing the mill rotated through an angle

of approximately 60° from that shown in Figure 2;

Fig. 6 is a longitudinal sectional view of a tumbling mill but showing a different discharge means than that shown in Figure 1 and also showing a modification in the conduits which constitute the feeding means, this section being taken on the line 6—6 of Figure 7;

Fig. 7 is a section on the line 7—7 of Figure 6;

Fig. 8 is a fragmentary diametrical section of a duplicate or twin construction;

Fig. 9 is a section on the line 9—9 of Figure 8, looking in the direction of the arrows;

Fig. 10 is a section on the line 10—10 of Figure 8, looking in the direction of the arrows but showing the manner in which the feed moves into the mill and the action of the cascade diagrammatically;

Fig. 11 is a like view to Figure 10 but showing the position of the feed and load when the mill has turned through approximately a quarter of a revolution.

Referring to these drawings and particularly to Figures 1 to 5, it will be seen that I have illustrated more or less diagrammatically a tumbling mill consisting of an outer shell 10 with the heads 11 and 12. The head 11 has the axially extending trunnions 13 and the head 12 has like trunnions 13. Disposed within the entrance trunnion is a trunnion liner 14 which extends through and is connected with an end liner 15. This trunnion liner 14 is engaged in any suitable manner with a spiral feed screw 16 of any ordinary or suitable character which scoops into a mass of pulp or material to be ground, lifts it up and by rotation, discharges it into the duct formed by the liner 14. The interior, or a portion of the interior, of the barrel or shell 10 is provided with the liner 17 which has a length practically equal to that of the grinding chamber 18 and this grinding chamber at its outlet end is closed or partially so by a transversely extending plate or liner 19, shown in Figure 1 as having a central grating or perforated portion 20 through which the comminuted material is discharged into the longitudinal liner 21. The mill may be operated in any suitable manner as, for instance, by the gear wheel 10^a.

So far I have described the necessary elements of an ordinary tumbling mill, it being understood that the grinding chamber 18 is to be partially filled to any extent required with balls, rods, pebbles, or other grinding elements, and that the unground material is discharged by the duct or liner 14 into the mill and the ground pulp or dry comminuted material is discharged through the screen or grate 20 and through the duct 21. My improvement consists in providing

means whereby the material fed to the mill shall be discharged into the grinding space 18 adjacent the perimeter or periphery of the mill. To this end I dispose within the 5 mill at the entrance end thereof, the feed conduit liner or plate 22 which extends entirely across the space defined by the shell 10 and is provided with the peripheral flange or rim 23 which bears against the barrel or 10 shell. Adjacent the periphery of this liner 22 and for a portion of the circumference of the liner, the liner is extended laterally forward as at 24, and then outward as at 25. The inner face of the liner is formed 15 with an outwardly projecting flange or rib 26 which, as shown in Figures 2 and 5, extends in an approximate spiral from a point intermediate or between the periphery of the liner and the center thereof more or less 20 concentrically around the center to a point adjacent the periphery and then extends outward, as at 27, to the periphery. A more or less spiral conduit 28 is thus formed which extends approximately three-fourths of the 25 circumference of the shell. Outward of this conduit 28 is a second conduit 29 formed in the opposite portion of the liner 22, which conduit begins at a point in advance of the termination 27 of the conduit 28, and extends 30 concentrically to this conduit 28 or extends circumferentially a relatively short distance. This second conduit 29 is separated from the first conduit for the greater portion of its length by a wall 30 but adjacent 35 the closed end of the conduit 29 formed by the inclined wall 31 there is an opening 32 in the wall 30 which permits the material collected in the conduit 28 at the blind or closed end thereof, to pass into the conduit 40 29 at or near the blind or closed end thereof. It is to be particularly noted in this connection that this opening 32 is disposed in advance of the end wall 27 of conduit 28 and that the opening 32 is disposed in advance 45 of the wall 31 of conduit 29 so that pockets 28^a and 29^a are thus formed, one at the termination of the conduit 28 and the other at the beginning of conduit 29. These pockets constitute important features of my invention as will hereafter appear.

It will be seen that the material which is gathered in the conduit 28 at the rear end thereof, will be discharged into the conduit 29 through opening 32 and discharged from 55 this conduit 29 into the grinding space 18. This obviously, as will be apparent hereafter, is always above the load line or the cascade line shown in dotted lines in Figures 2 and 5 and designated *a*. In Figure 60 2, the shell or barrel 10 of the mill is shown in such position that the opening 32 between the conduits is at its zenith, while in Figure 5, the mill is supposed to have rotated through approximately 60°, the mill rotat- 65 ing in a counter-clockwise direction as shown

by the arrows in Figures 2 and 5. While in Figure 1 the opening 32 is shown at its zenith, in Figure 3 the opening is shown at its nadir.

The operation of the construction illustrated in Figures 1 to 5 is as follows: The material to be comminuted is scooped up by feed spout 16 and fed into tube 14 from which it is discharged onto the concavely curved face of wall 26, as shown in Figure 2. 70 This conduit 28 is at all times free from load pressure and as the mill rotates this mass of material is carried along over the interior surface of wall 26 and so into the conduit 28 until it eventually arrives in the 75 pocket formed at the end of the conduit 28 by the wall 27. As the pocket passes to the zenith of its movement, the material tends to reverse its movement or, in other words, as this material moves back or down 80 the conduit, with the conduit in the position shown in Figure 5, some of the material, that contained within the pocket of the conduit, will move down this conduit in the direction of movement of the mill and will 85 be discharged through the opening 32 into the conduit 29 and eventually after successive revolutions, will be discharged into the grinding chamber above the load line *a* 90 therein or above the toe of the cascade. 95

Assuming that the mill has received its load until the face of the load under rotation would be as shown by the dot and dash line *a*, it will be noticed from Figure 5 that the materials to be picked up by the conduit 100 28 would have advanced about half way along the length of the conduit or be disposed almost immediately below the tubular feeding trunnion and at this point the conduit 29 has its inner end entering the 105 mill load. Thus, if either of these conduits were empty, both of the conduits would fill. It is also apparent, however, that any column of load filling the conduit 28 will have 110 a vertical depth or head which is greater than the depth or head of the load in the conduit 29 due to the greater length of the conduit 28 and its advanced position. Consequently any load in conduit 29 will 115 always be over-balanced by the load in conduit 28 and this will tend to cause a flow of the load from conduit 28 into conduit 29 through the opening 32.

During rotation and with the mill just beyond the position shown in Figures 2, the 120 loads of both conduits will fall forward in the direction of rotation, leaving the pockets of conduits 28 and 29 emptied or substantially so. The conduit 28 and its pocket because of their larger size, have a greater 125 capacity than the conduit 29 with its pocket and, therefore, the excess material in the pocket of conduit 28 flows laterally freely into conduit 29 and thus tends to assist the free lateral movement of material through 130

the opening 32 into conduit 29, thereby displacing the advanced material and forcing it into a radial plane which is within the scope of the grinding chamber. If both 5 conduits 28 and 29 were of the same size in cross section and relative radial position and did not have the pockets at the extremities of the conduits but terminated with the opening 32, there would be a lateral 10 passage from conduit 28 to conduit 29 due to the vertical head being greater in 28 than 29. By having the conduit 28 of greater 15 size and providing the conduits with the respective pockets, the lateral displacement of the feed in its movement from the plane of 20 conduit 28 to the plane of conduit 29 is very greatly aided. The mill is considered to be revolving about its longitudinal axis in a horizontal position. The tendency of the 25 falling load is to pass in a gravity plane which is normal to the mill axis. When a conduit such as described becomes filled, any particle of the load is held by adjoining parts from being laterally diverted by an inclined 30 wall of the revolving structure. If the mill were revolving at a speed greater than that of the tumbling load, it would develop an impulse to the load when any diverting face of the mill passed the load as, for instance, occurs in a centrifugal pump, but in cylindrical grinding mills the speed 35 of the mill is too low to make any such effect appreciable and the load falls in cascade upon a gravity plane without lateral influence. Under these circumstances, loads in adjoining radial planes tend to equalize and seek their natural level or repose when allowed freedom of movement.

Figure 4 shows a longitudinal section of 40 the feed conduits near the opening 32 when the pocket of conduit 28 is closed to the zenith of the circuit and illustrates the action of the load under these circumstances. In falling in cascade the normal load in conduit 28 will drop so that its upper surface will be close to the bottom of opening 32 and, therefore, the load contained in the pocket 28 will fall upon this surface and freely move into the conduit 29, thus placing the 45 excess diverted material within the conduit 29 rather than in the conduit 28. Figure 3 shows a cross section of the conduits taken on the same plane as Figure 1 but with the conduits inverted and this figure shows that 50 the conduit 28 has a greater vertical depth than conduit 29 and that thus the excess weight of material in conduit 28 will cause its load to surcharge the conduit 29 or any space formed above the normal load of conduit 29 as it freely settles to repose by gravity. It is, therefore, most desirable, though not absolutely necessary, that the conduit 28 shall have a greater depth than conduit 29 and have its end advanced over 55 the end of conduit 29. If the conduits 28

and 29 were of the same cross section, had the same radial position, and were similarly filled, then during rotation their loads would advance at the same rate but if the depth of conduit 28 in cross section be 70 greater than the sectional depth of conduit 29, it is found in actual practice that the advancing toe of the load in conduit 28 will have an advanced position over the toe of the load in conduit 29. Therefore, when 75 this advanced load of the larger conduit reaches the communicating opening 32, this load will spill laterally and some of the load in conduit 28 will take position in the smaller conduit 29 ahead of the material in 80 conduit 28 which is of less depth.

The blind ending of the conduits 28 and 29 causes the pockets thus formed at the ends of these conduits to virtually act as buckets in lifting their contained loads over 85 the center line and toward the cascading side. After these conduits have passed the vertical center line, the forward movement of the feed in conduit 29 discharges it into the grinding chamber at a point above the 90 mill load. While some of the load enters the lower end of conduit 29, as this conduit enters the mill load, yet conduit 29 does not become excessively filled due to the fact that it is already filled by the advancing 95 feed, the speed of the mill and the speed of the cascade not allowing sufficient time for the entire unloading of conduit 29. This conduit 29 tends to deliver its load as soon as the opening of the conduit passes 100 the vertical center line or approximately as soon as the opening of the conduit leaves the mill load and this discharge continues until conduit 29 has entered the mill load. Thus, this conduit 29 delivers its discharge 105 in the direction of its rotation and always into the space above the mill load. Accordingly the mill load can be enlarged until it entirely fills the mill. When this occurs no further discharge of feed is possible until the mill has discharged some of its load and then as soon as the space is provided for the feed, the conduit 29 will again begin to discharge.

The very important feature of advantage 110 in my construction is that by having the conduits 28 and 29 extending from opening 32 in the same direction, the contained loads within the two conduits are entirely protected from the mill load and thus the upper portions of the loads within the falling conduits are free to move laterally from one conduit to the other. Thus there is no impediment to the free movement of material from conduit 28 into conduit 29 and my 115 construction does away entirely with the difficulties heretofore experienced in feeding material into tumbling mills against the load therein.

The length of conduit 29 from the open- 120

ing 32 to the end of the conduit can be varied without ruining its effect but preferably and properly its length should be great enough so that as its contained load falls in cascade, the time factor and speed of the mill will not allow the conduit to fully empty. The speed of the mill is only slightly different from the movement of the load and before the conduit 29 can empty entirely, it again enters the load and all of the conduit load consolidates. The respective sizes of conduits 28 and 29 can be varied to suit conditions for developing the desired flow of feed and these conduits can be spiral in shape, that is, of various radial positions for special purposes. It is to be noted in Figure 2 that conduit 29 has a greater radial position than conduit 28, although conduit 28 is the larger conduit.

Reviewing the path or circuit for the feed: The feed enters scoop 16, is delivered through the trunnion liner 14, to the central chamber of conduit liner 22 where it enters the conduit 28 and passes counter to rotation towards the pocket 28^a. Here it passes laterally through opening 32 into the blind end of conduit 29 where it changes the direction of its travel to flow with the direction of rotation until it is discharged through the end opening of conduit 29 and is delivered into the vacant space above the load line or face of the load in the grinding chamber. Delivery is always made above the load and, therefore, it is possible to completely fill the grinding chamber regardless of the level of feed in the central entry chamber of the conduit liner 22.

In the construction illustrated in Fig. 1, the load within the mill can pass through the screen 20 and be discharged through the spout 21 near the axial line. Thus, it is apparent that the conduit 29 can discharge the feed to a full section of the mill if need be and that the hydraulic gradient between the points of feed and discharge can be controlled or established by this improved perimetric feed and by the nature and position of the discharge opening. The desired product of pulp is secured by adjusting the different conditions to suit and this is particularly true with regard to the length of the mill, the hydraulic gradient of the pulp, and the amount of loading. It will also be noticed that in the construction shown in Figure 1, the load may be enlarged within the grinding mill or chamber to closely fill the mill section and that thus only a low power is needed in order to drive the mill, as previously explained.

In the construction shown in Figures 6 and 7, the arrangement of the conduits 33 and 34 is similar to the conduits 28 and 29 with this exception, however, that no pockets are provided as in the described constructions and conduit 34 opens reversely to con-

duit 29 so that the product of feed is delivered within the grinding chamber counter to the rotation of the mill instead of in the same direction as the rotation. In this construction the mill load will prevent conduit 70 34 from discharging until its opening is clear of the load, as shown in Figure 7. Consequently the mill load will increase or the conduit 34 will discharge feed into the grinding chamber until the surface of the 75 load or cascade nearly meets the zenith of the mill interior when the loading action will cease for the reason that after the load in conduit 34 passes the vertical center line of the mill, the gravity effect on the load in conduit 34 will cause it to fall in the same direction as the rotation of the mill and thus it will remain within the conduit.

The loading thus made will approximate 55% of the mill section whereas the arrangement of conduits 28 and 29 permits the mill to be loaded to any proportion of its section or be entirely filled if necessary. Otherwise than as described above, the construction of the liner 22 and of the entrance end of the 90 apparatus is practically the same as before described and the same reference numerals have been used.

In the construction illustrated in Figures 6 and 7, however, I have illustrated the drum 95 or barrel 10 as being mounted upon the gear wheel 10^a and upon the track 35 which engages the rollers 36. This does away with discharging the feed through the hollow trunnion 21 and the discharge passes 100 through a grate 37 which extends entirely across the drum and has a solid central portion 38. The drum is provided at its discharge end with the drip flanges 39 which discharge into a launder or trough 40. A 105 hopper 41 discharges into the hollow trunnion liner 14. The open end construction which I have provided in Figure 6 permits an extension of the hydraulic gradient to the perimeter of the mill shell if need be, 110 thus effecting a rapid migration of the pulp under extreme gravity influence. Mill interiors are often provided with undulating inner surfaces or lifting lugs to assist in lifting the load during rotation but it is 115 apparent that the larger the load, the greater will be its surface friction with the liner and the grinding chamber and thus the less requirement there will be for any lug arrangement for holding the load rotation 120 to the speed of the mill rotation. I have not illustrated the liners in Figures 1 or 6 as being provided with lugs but I do not wish to be limited to the grinding chamber having a plain inner surface. In Figures 8 and 125 9 I have shown a modification or duplication of the mechanism illustrated in Figures 1 and 2. Cylindrical mills should be as closely balanced on their axis as is possible. By providing the twin conduits 28 and 29 130

the mill is made bilaterally symmetrical. These twin conduits can be concentric to each other or if limited within the range of 180°, they can be of duplicate design on each 5 side of a central line. This condition not only gives a balanced mill but likewise duplicates and increases the conduit discharge.

With my improved feed arrangement, it 10 is possible to charge feed into the mill as long as any space exists therein. The desired ball load can be installed and then the mill can be charged with pulp to any degree necessary to give proper control of feed conditions. The mill length should be designed 15 to secure a desired product so that the proper hydraulic gradient can be maintained in the pulp to maintain its rate of flow. The means for discharging the pulp from the mill may be of many different 20 forms but these are subsidiary to the feed mechanism illustrated. Figure 1 shows a construction wherein the discharge is controlled or kept at the mill trunnion level, whereas Figure 6 shows a construction 25 wherein the discharge extends to the perimeter of the mill. Thus two extremes are represented.

One very important point of advantage 30 of the perimeter feed is that the operator fills the mill to the desired ball load and then with my perimeter feed arrangement any desired amount of pulp can be fed to this ball load inasmuch as the feed of pulp is entirely independent of the amount of 35 the ball load in the mill. With an axial feed mill, a ball load just above the mill axis limits and determines the feeding of the pump and, therefore, the latitude of the mill operation is thereby limited.

40 It will be seen that in this mill, as illustrated, at the perimeter of the load the speed of the cascade is greater than the speed of the mill. Otherwise the perimeter speed of the load and the speed of the mill are closely similar and similar speeds and 45 forces are acting on the mill as well as on the load. The predominating forces are those of gravity, centrifugal force, and the reacting centripetal force, the overcoming 50 of any one of which involves an element of time. A discharging slope of repose of the material is duplicated in a similar slope upon filling at an opposite point of the circuit. To overcome these conditions, the conduits, 55 in the form of my construction shown in Figures 8 and 9, are extended in the same direction from the communicating opening, and this for certain periods insulates or separates the conduit action from the load 60 so that the conduit loads can move entirely freely to lateral slopes of repose. Thus, in Figure 11 it will be seen that the load in 29 shown at its nadir, does not even fill the conduit cross section because under the 65 motions and forces acting, an element of

time will be required for gravity to lower the load to the right to fill this space, the load to the right having a speed and gravity-centrifugal force which is the same as and equal to the load within the conduit. The conduit load at the left in Figure 11 can spill from the conduit 28 into conduit 29 and be fully protected from any obstruction or action by the mill load. If the conduit 29 were open at the left or rear, the mill load would enter and interrupt the load action of this conduit. Thus it will be noted that my arrangement of conduits permits the load to be transferred and move within the conduits independently of the mill load. The load, therefore, within the conduits moves regardless of the mill load but still has a power of progression into the grinding chamber when the open end of the conduit is lifted out of the mill load. Thus the mill load may be at a maximum, yet the central entry chamber defined by the wall 22 may be substantially empty. At all times, however, there is an unobstructed and continuous opening between the two chambers. 90

Another object and advantage secured by my construction is as follows:—In grinding feldspar in a ball mill, the feldspar is fed manually through the manhole until the mill is entirely filled. Then the manhole is closed and the mill is rotated but without load circulation. Then the entire load is removed through a screen, the screen acting to restrain the mill balls. The mill is entirely filled manually and after rotation the load consolidates, leaving a small vacant space above the cascade. With my construction I can close the screen at the discharge end, then entirely fill the mill, rotate the mill until the proper crush has been made, then open the discharge screen and allow the ground material to discharge under continued rotation, and then feed the next batch through the feed liner, thus making a batch load circulate in discharge after grinding and filling the next batch without opening the mill or inserting the load through a manhole. 105

110 As regards actual operation; with a trunnion feed, the space above the trunnion is air trapped but the perimeter feed can permit the air to escape back through the feed. Furthermore the cascade is open and any air pressure is permitted to escape through the discharge screen. 115

I claim:—

1. A tumbling mill including a shell or drum, a hollow trunnion at the entrance end of the shell and constituting a feed tube, and means disposed within the shell conveying the feed from the tube to the perimeter of the shell and including an approximately spiral conduit having one end disposed approximately concentric to the hollow trunnion and having the other end disposed at 120 125 130

the periphery of the shell, and a second conduit into which the first conduit discharges and extending concentrically to the shell and discharging at the perimeter of the grinding chamber of the mill.

2. A tumbling mill including a shell or drum, a hollow trunnion at the entrance end of the shell and constituting a feed tube, and means disposed within the shell conveying the feed from the tube to the perimeter of the shell and including an approximately spiral conduit having one end disposed approximately concentric to the hollow trunnion and having the other end disposed at the periphery of the shell, and a second conduit into which the first conduit discharges and extending concentrically to the shell and discharging at the perimeter of the grinding chamber of the mill, the second conduit being of less length than the first named conduit.

3. A tumbling mill including a shell or drum, a hollow trunnion at the entrance end of the shell and constituting a feed tube, and means disposed within the shell conveying the feed from the tube to the perimeter of the shell and including an approximately spiral conduit having one end disposed approximately concentric to the hollow trunnion and having the other end disposed at the periphery of the shell, and a second conduit into which the first conduit discharges and extending concentrically to the shell and discharging at the perimeter of the grinding chamber of the mill, the second conduit being of less length than the first named conduit and of less cross sectional area but disposed radially outward of the inner wall of the first named conduit.

4. In a tumbling mill, a grinding chamber and means for discharging feed into the grinding chamber at a point adjacent the perimeter of the mill and above the load therein, said means acting automatically to stop the feed when the load fills the chamber and automatically start the feed when the load has decreased sufficient to leave a space above the load.

5. A tube mill having a plurality of communicating feed conduits conveying feed from the axial center of the mill to the perimeter thereof, said conduits having different radial positions.

6. A tube mill having a plurality of communicating feed conduits conveying feed from the axial center of the mill to the perimeter thereof, said conduits having different radial positions and having different lengths therein of relatively different cross sectional area.

7. A tumbling mill including a rotatable shell having a feed conduit at its entrance end, and means disposed within the shell conveying the feed from said feed conduit to the perimeter of the shell including a conduit ex-

tending around the shell adjacent one end thereof and receiving feed from the first named conduit, the other end of the second named conduit being closed, a third conduit disposed inward of the second conduit and extending concentrically to and adjacent the perimeter of the shell, the third named conduit being closed at one end and discharging into the shell at its other end, the second named conduit adjacent its closed end having an opening into the third named conduit adjacent its closed end.

8. A tumbling mill including a rotatable shell having a feed conduit at its entrance end, and means disposed within the shell conveying feed from said feed conduit to the perimeter of the shell including a conduit extending around the shell adjacent one end thereof and receiving feed from the first named conduit, the other end of the second named conduit being closed, a third conduit disposed inward of the second named conduit and extending concentrically to and adjacent the perimeter of the shell, the third named conduit being closed at one end and discharging into the shell at its other end, the second named conduit adjacent its closed end having an opening into the third named conduit adjacent its closed end, the third named conduit discharging in the same direction as the direction of rotation of the shell.

9. A tumbling mill including a rotatable shell formed to provide a grinding chamber and having a feed trunnion at its center at the entrance end of the shell, and means disposed within the shell conveying the feed from said trunnion to the perimeter of the grinding chamber including a conduit extending around the shell adjacent the entrance end thereof and receiving feed from the trunnion, the outer end of the conduit being closed, a second conduit extending parallel to the first named conduit but toward the discharge end of the shell and extending concentrically to and adjacent the perimeter of the grinding chamber and discharging thereto, the second named conduit being closed at one end and both conduits having a communicating opening adjacent the closed ends of the conduits but disposed in advance of said closed ends, whereby to cause material to travel in the first named conduit reversely to the movement of the shell, the second named conduit discharging in the same direction as the direction of rotation of the shell.

10. A tumbling mill including a rotatable shell formed to provide a grinding chamber and having a feed trunnion at its entrance end, and means disposed within the shell for conveying the feed from said trunnion to the perimeter of the grinding chamber including a conduit extending around the shell inside thereof and adjacent the entrance end there-

of, said conduit receiving feed from the trunnion, the opposite end of the conduit being closed, a second conduit disposed parallel to but inward of the first conduit and extending concentrically to and adjacent the perimeter of the grinding chamber closed at one end and there being an opening between the conduits disposed inward of the closed ends of both conduits whereby to form pockets in the ends of the conduits, the first named conduit having its open end disposed in advance of its closed end whereby to cause material to travel in the first named conduit reversely to the movement of the shell, the second named conduit discharging in the same direction as the direction of rotation of the shell.

11. A tumbling mill including a shell having a head at its entrance end, there being a hollow trunnion discharging through said head, a liner plate disposed inward of the head and defining the entrance end of a grinding chamber, the plate being formed with a rib extending towards the head and defining an approximately spiral feed conduit, the conduit being closed at its outer end, the liner plate being also formed to provide a conduit offset to one side of the first named conduit of less cross sectional area than the first named conduit closed at its end adjacent the closed end of the first named conduit and terminating at its end short of the termination of said first named conduit, there being an opening between the conduits inward of the closed ends of both conduits, the second named conduit extending around the perimeter of the grinding chamber and being of less length than the first named conduit.

12. In a tumbling mill having a grinding chamber, means for discharging material to be treated into the grinding chamber at a point above the load therein and including a feed conduit carried by and rotatable with and opening into the grinding chamber and extending around the same, the discharge mouth of the conduit passing on each revolution downward into the load whereby the feed is stopped and being then carried above the load whereby the feed is allowed to flow by gravity into the chamber.

13. In a tumbling mill having a grinding chamber, means for discharging material to be treated into the grinding chamber above the load therein and including a plurality of conduits extending around the grinding chamber, carried thereby, and rotatable therewith, the conduits opening into each other, one of the conduits receiving material to be treated and acting by gravity to transfer the material to the adjacent conduit and one of the conduits opening into the grinding chamber, the discharge mouth of the last named conduit on each revolution of the mill passing down into the load and

being then carried above the load whereby to permit the feed within the conduit to flow down into the chamber toward the perimeter of the chamber onto the face of the load.

14. In a tumbling mill having a grinding chamber, means for discharging material to be treated into the grinding chamber above the load therein including a plurality of pairs of conduits, the pairs of conduits being arranged to balance each other, each pair including a conduit extending around the grinding chamber in an approximate spiral and receiving at one end the material to be treated and acting by gravity to cause the material to be transferred to the opposite end of the conduit, and the second conduit being closed at one end and at its other end opening into the first named conduit and then extending concentrically around the grinding chamber and discharging thereinto.

15. In a tumbling mill having a grinding chamber, a closed feed conduit having its entrance end communicating with a feed opening and its outlet end communicating with the interior of the grinding chamber, the conduit extending approximately concentric to the axis of rotation of the grinding chamber.

16. In a tumbling mill having a grinding chamber, and a hollow trunnion constituting means for feeding material into the mill, of means for carrying said material from said trunnion into the grinding chamber including two parallel conduits extending concentrically to the periphery of the mill one of said conduits being longer than the other and being disposed adjacent the inlet end of the mill and having an inlet end and a closed end, the inlet end communicating with the hollow trunnion, the shorter of the two conduits having a closed end disposed adjacent to the closed end of the longer conduit and having the open end discharging into the grinding chamber, there being an opening between the two conduits adjacent to the closed ends.

17. A tumbling mill including a rotatable grinding chamber, and tubular conduits disposed within the grinding chamber for directing the material to be ground from a point adjacent the axis of the grinding chamber to the perimeter thereof, said conduits freely discharging at the perimeter of and into the grinding chamber and in the same direction as the direction of rotation of the mill.

18. A tumbling mill including a rotatable grinding chamber, and a tubular spiral conduit disposed within the grinding chamber open to receive material at its inner end and discharging said material at the perimeter of and into the grinding chamber in the same direction as the direction of rotation of the mill.

19. In a tumbling mill, a grinding cham-

ber, and means freely discharging feed into the grinding chamber at a point adjacent the perimeter of the mill and discharging the feed in a direction the same as the rotation of the mill and above the load therein.

20. In a tumbling mill having a grinding chamber, means for discharging material to be treated into the grinding chamber at a point above the load therein and including a plurality of connected tubular feed conduits rotatable with and opening into the grinding chamber and extending around the same, the material to be treated passing successively through the connected conduits, the last conduit of the series discharging in the same direction as the direction of rotation of the mill.

21. In a tumbling mill having a grinding chamber, means for discharging material to be treated into the grinding chamber at a point above the load therein, said means including a plurality of connected parallel conduits, the first conduit of the series receiving a load at the axis of the mill, the last conduit of the series discharging the load at the perimeter of the mill, the feed conduits extending approximately concentrically to the axis of rotation of the mill and being rotatable with the grinding chamber.

22. In a tumbling mill having a grinding chamber, a tubular conduit for conducting material from the exterior of the mill into the grinding chamber, said conduit being so formed as to permit material within the conduit to move along the conduit independently of the load in the grinding chamber and freely discharging into the grinding chamber whenever the mouth of the conduit is lifted above the load therein, said discharge being in a direction that same as the direction of rotation of the mill.

23. In a tumbling mill having a grinding chamber, a tubular feed conduit having its entrance end communicating with an axial feed opening for the passage of incoming material and having an unobstructed outlet end extending in a similar direction to the perimeter of the grinding chamber and communicating with the interior of the grinding chamber, said conduit extending approximately concentric to the axis of rotation of the grinding chamber.

24. A tumbling mill including a grinding chamber, means for introducing material into the mill at the longitudinal axial center thereof, and a tubular feed conduit receiving said material at said axial center, the conduit extending approximately concentrically to the axis of rotation of the grinding chamber and advancing the material from the center toward the perimeter of the grinding chamber and simultaneously advancing the material longitudinally of the grinding chamber, the conduit discharging at the perimeter of the grinding chamber

and in a direction at an angle to the longitudinal axis of the mill and above the load therein.

25. A tumbling mill including a rotatable grinding chamber and means for taking material at a point in line with the axis of the mill and directing said material to the perimeter of the mill including circumferentially elongated tubular conduits rotatable with the grinding chamber, the conduits being connected to each other and being disposed at different radial distances from the axial center of the mill, the conduits freely discharging at the perimeter of and into the grinding chamber.

26. A tumbling mill including a rotatable grinding chamber, and means for taking material from a point coincident with the axis of the mill and discharging the material at the perimeter of the grinding chamber including circumferentially elongated tubular connected conduits disposed within the mill, the conduits being so formed as to convey the material radially and axially and the last conduit of the series discharging at the perimeter of and into the grinding chamber.

27. A tumbling mill including a grinding chamber, means for introducing material into the mill at the longitudinal axial center thereof, tubular means for conveying said material into the grinding chamber and discharging the material adjacent the perimeter of the grinding chamber, said tubular means extending parallel to the direction of rotation of the grinding chamber and including an extension into which the tubular means discharges in a direction parallel to the longitudinal axis of the grinding chamber, said extension discharging parallel to the plane of rotation of the grinding chamber and extending in opposite directions beyond the discharge opening of the first named tubular member.

28. In a tumbling mill, a grinding chamber and means for discharging material to be treated into the grinding chamber at a point above the load therein including a tubular feed conduit rotatable with and opening into the grinding chamber and extending around the same, the feed conduit being approximately spiral and receiving material at the axis of the mill, the conduit extending outwardly and circumferentially to the perimeter of the mill and having a longitudinally displaced portion open at one end and discharging at the perimeter of the grinding chamber and in the plane of movement of the grinding chamber.

29. In a tumbling mill having a grinding chamber, means for discharging material to be treated into the grinding chamber at a point above the load therein including two connected, parallel conduits, the first conduit of the series being disposed at the entrance end of the mill and receiving a load

from the axis of the mill, said conduit extending spirally around the mill to the perimeter thereof, and the second conduit extending parallel to the first named conduit but reverted with relation thereto and into which the first named conduit opens, the second named conduit having a cross sectional area less than that of the first named conduit whereby the load in the first named conduit will overbalance the load in the second named conduit and prevent retrogression of the load in the second named conduit.

30. In a tumbling mill having a grinding chamber, an axial feed opening, a conduit through which material is advanced by rotation of the mill having its entrance end in communication with the feed opening and its discharge end facing in the direction of

rotation of the mill and adjacent to the 20 perimeter of the grinding chamber.

31. In a tumbling mill having a grinding chamber, an axial feed opening, a conduit through which material is advanced by rotation of the mill having its entrance end 25 in communication with the feed opening and its discharge end disposed adjacent the perimeter of the grinding chamber, and means at the discharge end of the conduit preventing the return movement of the load into the 30 conduit but permitting the discharge of load from the conduit into the grinding chamber when the mouth of the conduit rises above the load in the grinding chamber.

In testimony whereof I affix my signature.

NEWTON L. HALL.
